UNITED STATES PATENT OFFICE.

GEORGE W. BALDWIN, OF SCHAGHTICOKE, NEW YORK, ASSIGNOR OF ONE-HALF TO GEORGE H. STEVENSON, OF SAME PLACE.

PEN-HOLDER.

SPECIFICATION forming part of Letters Patent No. 404,027, dated May 28, 1889.

Application filed June 19, 1888. Serial No. 277,567. (No model.)

To all whom it may concern:

Be it known that I, GEORGE W. BALDWIN, a citizen of the United States, residing at Schaghticoke, in the county of Rensselaer and 5 State of New York, have invented new and useful Improvements in Pen-Holders, of which the following is a specification.

My invention relates to pen-holders, primarily, and has for its object to furnish a 10 pen-holder which by a simple and inexpensive mechanism connected therewith may be made to accommodate either a large or small pen, or may be readily made into a fountain-pen by substituting a fountain for the small 15 pen.

With these objects in view my invention consists in the improved construction, arrangement, and combination of parts herein-after fully described, and afterward specifically pointed out in the claims.

In the drawings, Figure 1 is a perspective view of a pen-holder constructed with my improvement, a portion of the outer tube being removed to clearly show the interior construction. Fig. 2 is a similar view, a large pen being inserted and properly secured therein. Fig. 3 is a similar view with a small pen inserted and secured. Fig. 4 is a smaller view with a large pen and fountain inserted 25 and secured, and Figs. 5 and 6 are detailed views showing modifications of the cam or eccentric clamping or securing mechanism.

Like letters of reference mark the same parts in all the figures.

Referring to the drawings, A is the pen staff or handle, upon the end of which is fitted a tube, B, as is ordinarily the case. Within this tube are located the various parts of the mechanism which forms my improvement.

C and D are two partial sections of cylinders or curved plates bent on curves of less radii than that of the tube B, the radius of the curved plate D being also slightly less than that of the plate C. These plates are loosely 40 secured within the tube B by means of a pin, E, passing through slots in said plates. The

tube B is provided with a slot, b, in which works a cam or eccentric, F, pivoted on a pin, G, secured in the sides of the tubes. When the curved plates C and D are in place in the 50 tube, as described, spaces H and I are provided, the former between the tube and the plate and the latter between the plates C and D, the former being on a larger curve than the latter. Into the space H a large pen may 55 be placed, and into the space I a small pen, either of which may be securely clamped by the manipulation of the cam or eccentric F in the well-known manner by turning down upon the inner plate, D. This turning may 60 be effected by the lever f or by the milled surface shown in Fig. 5.

The eccentric may be made to operate with a spring-pressure by the means shown in Fig. 5, h being a spring secured to its contact- 65 surface.

In order to form a fountain-pen, the fountain J may be used in connection with the large pen, as shown in Fig. 4.

Having thus fully described my invention, 70 what I claim, and desire to secure by Letters Patent, is—

1. A pen-holder provided with a curved plate loosely secured within the tube, and a cam, whereby a pen may be clamped between 75 the curved plate and the tube by means of the cam, as set forth.

2. A pen-holder provided with two curved plates loosely secured within the tube, and a cam, said plates being of different curves, as 80 set forth.

3. A pen-holder provided with two curved slotted plates, a pin passing through the slots and secured to the tube, and a cam-clamp operating to secure a pen in the holder, as set 85 forth.

In testimony whereof I affix my signature in presence of two witnesses.

GEORGE W. BALDWIN.

Witnesses:

GEORGE F. ALLEN,
FRANK C. BALDWIN.
